UNITED STATES PATENT OFFICE.

EDWARD FRANK CUMISKEY, OF MILWAUKEE, WISCONSIN.

AUTOMATIC POWER-OPERATED RACKING MECHANISM FOR KNITTING MACHINES.

Application filed August 27, 1921. Serial No. 495,928.

To all whom it may concern:

Be it known that I, EDWARD FRANK CUMISKEY, a citizen of the United States, residing at Milwaukee, in the county of Milwaukee and State of Wisconsin, have invented certain new and useful Improvements in Automatic Power-Operated Racking Mechanisms for Knitting Machines, of which the following is a specification, reference being had to the accompanying drawings.

This invention relates to flat bed knitting machines, and particularly to means designed to cause the automatic racking of the needles, this means being adapted either as an attachment to be used in converting flat hand knitting machines to power operated knitting machines or being built in as part of new machines, the machine being either driven by an electric motor, by a belt, or being either plain, semi-automatic or full automatic.

The general object of the invention is to provide pattern controlled means for causing the needle beds of flat knitting machines to move from center to center of the needles in either direction.

A further object is to provide pattern controlled, power operated means for relatively shifting the needle beds of flat knitting machines of such character that many different kinds of work can be performed with the attachment, and more specifically to provide a machine of this character so designed that it may be quickly adjusted or set up for any of the following parts of garments: backs, fronts, sleeves, pockets, cut collars, borders, zigzag patterns, and in fact to provide pattern controlled means whereby anything that can be made upon a flat bed knitting machine by hand can be made automatically.

And a further object is to control the relative shifting of the needle beds by means of one or a plurality of pattern wheels and to do away with the use of a pattern chain, the pattern wheel being simpler in construction, costing but a fraction of what chain attachments cost to operate, and being capable of being set up in half the time it takes to set up a chain or other pattern control machines.

A still further object is to provide these pattern wheels with removable pins which may be easily put in place and removed and which control the shifting of the needle bed, and in this connection to provide means

whereby after the pins are once set up they may be locked in place so as to prevent any possible accidental shifting or disengagement of the pattern producing pins.

60

Another object is to provide two pattern wheels, each having a capacity of 250 rounds each, the second pattern wheel being automatically started after the first pattern wheel stops, and to provide means whereby after the second pattern wheel has made a complete rotation it will again start up the first pattern wheel, thus securing a required number of rounds, which could not be had with a single wheel with any special number 70 of teeth.

65

Still another object is to provide means controlled by the pattern wheels whereby the machine is automatically stopped on any round desired, this stoppage of the machine 75 at any number of rounds the garment may require permitting the changing of yarn, decking, widening or fashioning of the goods being made on the machine, which, of course, is done by hand and furthermore causes the garments or work to be made uniform in length.

70

A further object is to provide a single action dog to operate the rack cam, said dog being so designed as to be positive in its 80 action so that it will be practically impossible for it to be wedged or broken and which cannot engage two opposite teeth at the same time, a fault which is present in other machines known to me and which causes breakage, loss of time, and expense.

85

Another object is to provide a clutch operating means which can be adjusted or set without stopping the machine and by which the machine can be stopped so quickly at 95 either end of the stroke that the operator does not have to move the machine in place by hand at the end of the stroke to do transferring of stitches or carrying on any other work necessary in the operation of the knitting machine.

90

Other objects will appear in the course of the following description.

My invention is illustrated in the accompanying drawings, wherein:

105

Figure 1 is a front elevation of a knitting machine constructed in accordance with my invention;

Figure 2 is a top plan view of the construction shown in Figure 1, but with the 110 needle beds and the knitting mechanism for the needles removed.

- Figure 3 is a fragmentary end elevation of the machine shown in Figure 1 looking toward the pattern wheels;
- Figure 4 is a detail elevation of a portion of one of the pattern wheels showing a portion of the pattern wheel shifting mechanism and illustrating the needle bed ratchet and the double dog therefor, the shafts 26, 75 and 104 being in section;
- Figure 5 is an end elevation of the needle beds showing the shaft 75 and the means thereon for actuating the needle beds;
- Figure 6 is an elevation of the needle bed shifting cam;
- Figure 7 is an elevation of the needle bed shifting ratchet and its locking means;
- Figure 8 is a perspective view of the needle bed shifting yoke with which the cam 81 coacts;
- Figure 9 is a perspective view of the double dog for actuating the ratchet 76 and of the rocker arm;
- Figure 10 is a perspective view of the track member for supporting the double dog;
- Figure 11 is a perspective view of the lever 121;
- Figure 12 is a cross sectional view through the table 10, showing in elevation the clutch actuating device;
- Figure 13 is a perspective view of the clutch shifting lever;
- Figure 14 is a longitudinal sectional view of the clutch;
- Figure 15 is a perspective view of the knock-off rod whereby the clutch is knocked off;
- Figure 16 is a perspective view of the pattern dogs;
- Figure 17 is a fragmentary edge elevation of the pattern wheels showing how the pattern wheels are mounted;
- Figure 18 is a perspective view of the automatic stop mechanism;
- Figure 19 is a perspective view of the bracket supporting the knitting machine;
- Figure 20 is a perspective view of the member connecting the movable needle bed to the yoke in Figure 2;
- Figure 21 is an elevation of the conjoined cams 103 and 124;
- Figure 22 is a section on the line 22—22 of Fig. 21;
- Figure 23 is a sectional view showing the means for holding the cams 124 and 103 in place;
- Figure 24 is a perspective detail of one of the pattern pins;
- Figures 25 and 26 are inside fragmentary face views of the two pattern wheels 115 and 116.
- Referring to these drawings, it will be seen that I have illustrated therein a flat bed knitting machine of the ordinary type, wherein the usual carriage is provided and a slide therefor, and wherein the needle bed is shiftable. The needles are arranged in two straight, parallel rows and the fabric passes down between them as it is knitted. The two rows of needles are disposed opposite each other in grooves in the steel needle beds 8 and 9, the two sides of which beds slope from each other and which are separated at their upper ends so that the needles may form the stitches. The usual carriage is propelled by crank back and forth over the needle bed, the carriage supporting a lock for shifting each row of operating needles up and down in the grooves and carrying the usual yarn guide for delivering the yarn from the bobbin to the hooks of the needles as they are moved up by the cams. As the carriage is driven over the needle beds the needles are driven up and drawn down by the cams forming stitches with one revolution of the usual crank. In using machines of this character the stitches may be varied by shifting the movable needle bed 9 relative to the stationary needle bed 8. The movable bed is shifted in either direction according to the distance between the needles.
- As before stated, the object of this invention is to provide means whereby this movable needle bed may be shifted relative to the fixed needle bed to an extent depending upon the shifting of the cam with which the machine is provided, as will hereafter appear.
- Referring to the drawings, 10 designates a plate or table above which the needle beds are mounted, this plate or table being provided with legs 11 whereby it may be supported, and engaged with each other by longitudinal and transverse braces 12 and 13. This table is bolted to the legs and may be made in any suitable manner. Bolted upon one end of the table 10 is a supporting plate 14 which is provided with bearings for the support of a shaft 15 and with bearings for the support of a parallel shaft 16, and with rearwardly projecting arms 17 formed at their ends to provide bearings for a handle shaft 26, as will later appear.
- Mounted upon the shaft 15 is a fixed cone clutch member 18, (see Figures 3 and 14) and slidably mounted upon this shaft 15 is a gear wheel 19 which, as illustrated, is milled. While I have referred to this wheel as being a gear wheel, I do not wish to be limited to this, as will hereafter appear. This gear wheel 19 is slidable upon the shaft 15 and coacts with the cone clutch member 18 so that when the wheel 19 is shifted toward the clutch member 18 in Figure 2, it will engage the clutch 18 and power will be transmitted from the wheel 19 to the shaft 15, and vice versa when this wheel 19 is shifted away from the clutch member 18 it will run freely upon the shaft 15. This

gear wheel 19 is illustrated in Figure 3 as being driven by a gear wheel 20 mounted upon the shaft 16, this shaft carrying at its outer end the pulley wheel 21 which is 5 illustrated as connected by a belt to the electric motor 22. Preferably the gear wheel 19 is housed within the cover or shield 23. The shaft 15 carries upon it a pinion 24, which in turn engages a relatively large 10 gear wheel 25 mounted upon a shaft 26 supported in bearings on the arms 17. The gears 24 and 25 are preferably housed or shielded so as to prevent any danger of the operator coming in contact with these 15 gears.

The shaft 26 carries upon its outer end remote from the gear wheel 25 a crank arm 27 carrying a crank handle 28. This crank handle 28 carries upon it a socket 29 from 20 which a link rod 30 runs to the carriage to which it is pivotally connected. It will be obvious, therefore, that as the handle 28 is operated, the shaft 26 will be rotated and at the same time the link 30 will be reciprocated, thus reciprocating the carriage. This 25 is the usual and ordinary manner of reciprocating the carriage and forms no particular part of my invention. The crank arm 27 is U-shaped in cross section, and inserted in the recess so formed is a longitudinally extending bar 31 which forms the means for adjusting the length of stroke of the machine to the proper travel of the carriage according to the work that is to 30 be made. Forming part of the hub of the crank arm 27 is a weight 32 projecting out oppositely to the crank arm so as to counterbalance the same and make the machine steady in operation.

40 It will be obvious now, that assuming the gear wheel 19 is engaged with the clutch member 18 that power communicated to the shaft 16 will be transmitted through the gear 20 to the gear 19 and thence to gear 24, thence to gear 25, thence to shaft 26 and so to the handle 27 and the carriage will be reciprocated, and vice versa the carriage may be reciprocated and the knitting machine operated by turning the crank arm 50 27 by hand.

In order to provide means for shifting the gear wheel 19 which forms a clutch member and shifting this gear wheel quickly and accurately to clutch or unclutch the machine, I provide an oscillatable disk 34 (see Figure 2 and Figure 12) having a stud 33. This disk is mounted on a vertical bolt 35 extending through the slide 36 which is slidably engaged over an aperture 37 in 55 plate 10 and is adjusted by means of an adjusting screw 38. Mounted upon a stud 33 is a lever 40 which constitutes a shipper lever, this lever being provided at one end with the usual shipper fork 40^a adapted to 60 65 be connected in the usual manner to the hub of the shiftable gear wheel 19. It will be obvious that when this lever 40 is shifted in one direction, the gear wheel 19 will be withdrawn from engagement with the clutch 18 and when it is shifted in the reverse direction the clutch 18 and the gear wheel 19 will be engaged with each other. The stud 33 passes through an elongated aperture 38^a in the end of the lever 40. The disk 34 is provided with a handle 41 70 75 whereby the disk may be rotated.

It will be obvious that when the disk handle 41^a is shifted away from the operator who stands in front of the machine that the clutch will be thrown out and that when the handle 41 is shifted toward the operator the clutch will be thrown in and that this lever 40 is operated by means of the crank action of the stud 33. This action is very quick and certain. The device is extremely simple, practical and inexpensive, and by turning the adjusting screw 36 the initial position of the clutch can be readily set. This device is positive in its adjustment and needs no attention whatsoever and by its use, because of the quickness of its action, the machine can be stopped at either end of the stroke so that the operator does not have to bring the machine in place by hand at the end of a stroke to transfer stitches, narrow, or do any other work necessary. Of course, it will be understood that the fork 40^a is provided with the usual bronze shoes which reduce as much as possible the wear of this fork in relation to the hub of gear 19. This 80 85 90 95 handle 41 is operatively connected, as will be later stated, to automatic means for shifting the handle to release the clutch.

In order to automatically stop the machine by means of suitably adjusted stop pins on the pattern wheels, as will hereafter appear, I mount beneath the plate 14 in suitable bearings a double-armed trip lever 64 (Figures 1 and 18) which embraces the pattern wheels and which is mounted upon the shaft 65 having an arm 66, this arm having a convexly curved edge face 67. Mounted above the table 10 is a stop bar or rod 68, one end of which is angularly bent, as at 69, so as to extend beneath the clutch 105 operating handle 41, the other end of this bar being engaged by the edge face 67 of the arm 66. A spring 70 acts to urge the stop rod 68 in a direction to cause its angular end 69 to engage with the handle 41 110 and shove the handle over so as to throw out the clutch, but normally the stop rod 68 is held from this longitudinal movement by being formed with a notch 71 which engages with a stop bar holding plate 72 which is 115 angular in form, which is bolted to the table 10, and which is also notched to form a guide for the rod 68. At the proper time, as will hereafter appear, the trip lever 64 is 120 actuated by a pin on the pattern wheel and 125 130

this shifts the arm 66 upward and the rounded face 67 of the arm strikes the under side of the extremity of the rod 68, lifting this end of the rod so that its notch 71 clears the flange of the holding plate 72 or latch and then the spring 70 acts to retract this rod 68 so as to shift the clutch handle 41 and thus shift the clutch to its off position. This rod 68 is guided by means of a guide 73 bolted to the table 10.

For the purpose of causing the racking of the needle bed, I mount upon the plate 14 a supporting plate or bracket 74 which is provided with bearings for a transversely extending shaft 75. This shaft carries upon it a ratchet wheel or disk 76 (see Figures 4 and 7) having two series of reversely arranged teeth 77 and 78. I have illustrated the ratchet as provided with three teeth 77 and three teeth 78 and a tooth 79 which is disposed on the diametrical plane of the ratchet and which coacts with either of the sets of teeth 77 and 78. It will be understood that I have illustrated four teeth in each set but that the ratchet wheel may be milled to provide a greater number of teeth. The teeth are arranged to produce a one-needle movement of the needle bed to each tooth. A spring actuated dog 80 mounted upon the bracket 74 engages the notches in the ratchet 76 so that the ratchet, the shaft, and the cam 81 which is also mounted upon this shaft cannot move after the ratchet and the cam have been adjusted by the rack dog. This ratchet is designed to cause an oscillation of the shaft 75, and mounted upon the shaft 75 is the cam 81 (Figure 6). Disposed upon the shaft for reciprocating movement is a slotted yoke 82 (Figure 8) formed at its middle with an elongated slot 83 through which the shaft 75 passes, this yoke at its ends being provided with two rollers 84 which bear against opposite faces of the cam 81. One of these rollers is fixed and the other roller is adjustable by means of the adjusting screw 85. This yoke 82 has an inclined upper face 86 formed with bolt holes for engagement with an angular arm or plate 87 (Figures 1 and 20) whose opposite end is engaged with the needle bed 9 by the bolts 88. It will be obvious now that as the shaft 75 is oscillated, the cam 81 will cause a reciprocation of the yoke 82 and of the needle bed to an extent depending upon the degree to which the cam 81 is turned. It will be understood, of course, that this cam 81 is milled to suit the gauge of the needle bed. The means illustrated in Figure 7 and formerly described are provided for preventing the shaft 74 with the ratchet 76 and cam 81 from overrunning. Other suitable means may be used, however, for this purpose.

For the purpose of oscillating the ratchet 76, I provide a double toothed feed dog 91

(Figures 4 and 9). The teeth 92 and 93 of this feed dog are spaced apart such a distance that when one of the teeth is in engagement with the ratchet, the other will be out of engagement with the ratchet and that when this feed dog is in a neutral position, neither of the teeth will be engaged with the ratchet or affect the ratchet in any way. This feed dog is mounted for vertical adjustive movement and for longitudinal reciprocating movement. The feed dog is angularly bent and at its rear end is mounted upon a rocker 94. This rocker, as illustrated in Figure 9, is somewhat triangular in form and terminates at its lower end in a downwardly extending tongue 95. Between its ends the rocker rotates on a stud 96 carried on an arm 97 projecting from a bracket attached to the under face of the plate 14. This arm is forked at its rear end to provide bearings 98 and 99 for the shafts 26 and 104, as illustrated in Figure 4. The lower extremity 95 of the rocker is connected to a spring 100. The rocker is bifurcated at its upper end for the reception of the rear end of the feed dog 91 which is pivoted to the rocker, as at 101, and the rear end of the rocker carries a roller 102. Disposed upon the shaft 26 immediately behind this roller 102 is an elliptical cam 103 and as this cam revolves it causes the rocker to reciprocate toward and from the ratchet wheel 76, the spring 100 acting to shift the upper end of the rocker toward the cam 103 and keep the roller 102 in contact with this cam. It is necessary to provide means whereby the ratchet wheel 76 may be moved in one direction or the other and this is the reason for providing the double toothed dog 91, and it is necessary to provide pattern controlled means whereby either dog 92 or 93 may be shifted into engagement with the ratchet.

To this end, I mount upon a stud 104 carried on the extremity of the bracket 98 the pattern controlled lift levers 105 and 106 (see Figure 16) these levers being duplicates of each other. Each lever rearward of its pivotal axis 104 is provided with a tail 107 which tails are used to lift these levers by hand and to turn the pattern wheel by hand, as will be later explained. Each of these levers on its under side and intermediate its ends is formed with a downwardly extending tooth or lug 108, these lugs on the two levers 105 and 106 being controlled by pattern pins, as will hereafter appear. The forward end of each lever is shown as having pivoted to it an angularly bent member 109 providing what may be called a track 110, these two tracks extending beneath a transversely extending, cylindrical pin 111 on the bottom of the feed dog 91. Each of these members 109 has a downwardly extending arm 112, and a spring 113 is con-

nected to the lower end of this arm and to the corresponding pattern lift lever. This spring acts to urge the member 109 upward but a stop 114 prevents the spring from 5 raising the track 110 above a certain height. This spring actuated track 110 acts to safeguard against breakage of the pattern lift levers 105 and 106 which, if they were impeded in their movement or became wedged, 10 would have a tendency to break. By the provision of this resilient safety device 109, however, all possible chance of breakage is eliminated.

There are two pattern wheels 115 and 116 15 and these are mounted upon a stud 117 carried by a downwardly depending bracket 118 (see Figures 4 and 17). This bracket is formed with an upwardly extending lug 119 which has an aperture for a pin or stud 120, and mounted upon this pin or stud is a feed lever 121 which is disposed, as illustrated in Figure 17, in spaced relation to the outside face of the pattern wheel 116. This lever 121 below its pivotal support 120 is 20 provided with a tail 122, to which a contractile spring 123 is attached, which spring is also attached to the bracket 118 (see Figure 4). The upper end of this feed lever 121 is thus urged rearward and against an 25 elliptical cam 124 mounted upon the shaft 26. The upper end of this feed lever carries a roller 125 against which the cam 124 engages, and below this roller the feed lever is provided with a laterally projecting pin 30 upon which is mounted a feed dog 126 which extends across both pattern wheels. It will be obvious now that as the cam 124 is rotated, an oscillating motion will be 35 given to the feed lever 121 which will cause the feed dog to act upon the teeth 127 of the pattern wheels and to give a step by step motion to these pattern wheels.

The pattern wheels 115 and 116 are rotatably supported by the bracket 118 upon 40 a stud or bearing 117 (see Fig. 17). Each of these pattern wheels is formed with a hub 128 and these pattern wheels are spaced apart by a spacing washer 129. Between this washer 129 and the pattern wheels are 45 disposed fiber friction washers 130 and between the hub of the pattern wheel 126 and the bearing on bracket 118 is also a friction washer 130. Disposed outward of the hub of pattern wheel 115 is a spacing washer 131 which is keyed to the pin 117 to prevent it 50 turning, and between this washer 131 and the adjacent hub is another fiber friction washer 130. Bearing against the washer 131 is a coiled compression spring 132, which in turn is engaged by a disk or washer 133, which in turn is engaged by a nut 134 on the reduced extremity of the spindle 117. The whole purpose of these several washers 129, 130, 131, 133 and the spring 132 is to cause 55 sufficient friction on the pattern wheels to

prevent the wheels from moving too freely. If it were not for these washers, the pattern wheels would not stay in place but would move ahead or backward. In other words, they would overrun. The friction washers, 70 however, constitute means whereby friction is applied to the pattern wheels to prevent any overrunning and to hold them in the place to which they are turned or shifted by the feed lever 121. 75

As before stated, the peripheral faces of both of the wheels 115 and 116 are provided with ratchet teeth 127 with which the feed dog 126 engages. At one point in the periphery of each wheel a tooth is cut out, as 80 at 135, (see Figure 4) and after the feed dog 126 has oscillated the number of times that there are teeth 127 upon a wheel and arrives at the space 135, that particular wheel will stop. Each wheel may have any 85 number of teeth but for illustration I will assume that each wheel has 250 teeth 127. Extending from the outside face of each wheel are a number of holes or sockets 136 designed for the reception of certain pattern 90 pins 137. These pattern pins are provided with rollers. (See Figure 24.) Any number of pattern pins may be set in the holes 136, as will appear hereafter. There are 250 95 sockets or holes 136 in the outer row of holes, each hole being disposed immediately beneath one of the teeth 127. Immediately inward of the holes 136 there is a series of holes 138, into any one of which the pattern pins 137 may be disposed. There are the 100 same number of holes 138 as there are holes 136 and it may be remarked in this connection that there are holes 136 and 138 immediately beneath the cut-out portion 135, that is the points on the peripheries of each 105 wheel where a tooth is omitted. Inward of the series of holes 138 is a series of holes 139 in which stop pins 140 may be placed, these 110 stop pins being adapted to engage and shift the stop dog 64. Now it will be understood that the pins 137 and the holes 136 and 138 are intended for the purpose of actuating the pattern lift levers 105 and 106, while the pin or pins 140 disposed in any one of the holes 139 are for the purpose of stopping the machine. 115

Only one of the wheels 115 or 116 operate at one time. For instance, assuming that the wheel 115 be started and the feed lever 121 be given oscillation by the cam 124, it 120 will be obvious that the wheel 115 will be a step by step rotation for 250 steps and at this time the feed dog will reach the place of the omitted tooth 135 and the wheel 115 125 will stop. Just at this time, however, the wheel 115 communicates its motion to the wheel 116 and shifts this wheel 116 so that the pawl 126 engages the first tooth of the wheel 116 beyond the stopping point 135 130 so that the second wheel is started immedi-

ately upon the stoppage of the first wheel. This second wheel continues to revolve until it has made a complete revolution and then automatically starts the first wheel again, and so on.

This starting of one wheel from the other is accomplished by two pins 141 and 142 disposed respectively upon the confronting faces of the wheels 115 and 116. These pins are disposed each in the path of movement of the other pin. Thus, for instance, assuming that the pin 141 is temporarily in advance of the pin 142, it follows that upon a complete rotation of the wheel 115 that the pin 141 will come up to a position behind the pin 142 on wheel 116 and that the last stop of the wheel 115 will cause therefore a forward movement of the wheel 116 by the pin 141 contacting with the pin 142 and thus the wheel 116 will be caused to advance. This wheel 116 makes one complete revolution until its pin 142 comes around behind pin 141, whereupon it again starts up wheel 115. The pins 137 which are disposed within the sockets or holes 136 or 138 are held in place by an annular pin guard 143 (Figure 1) which is preferably made in one piece and has a width just sufficient to cover the holes 136 and 138, this pin guard having inwardly projecting lugs 144 through which screws 145 pass into the holes 139. These lugs obstruct these holes 139 but very slightly so that they do not practically interfere with the placing of the stop pins 140. The only purpose of this pin guard is to keep the pattern pins from falling out of the wheel, due to vibration, handling, etc. It will be noted from Figure 4 that the depending lug or tooth 108 of the pattern lift levers 105 and 106 extend downward between the pin guard and the face of the corresponding wheels 115 and 116 and are adapted to be engaged by the pins 137, or more properly by the rollers mounted on these pins.

Referring to Figure 4, it will be seen that if there are no pins in either the holes 136 or the holes 138 that the pattern lift lever corresponding to the particular wheel under consideration will drop to its lowest extent so that the tooth 92 will be engaged with the teeth of the ratchet wheel 76 and thus the ratchet wheel 76 will be given a counter-clockwise step by step rotation so long as this pattern lift lever is in its lowest position. If, however, a pin 137 is disposed in one of the holes 136, then the corresponding pattern lift lever will be raised and this will raise the dog 91 so that the tooth 93 will engage with the ratchet wheel 76 and a reciprocation of this dog 91 will cause a movement of the ratchet wheel 76 in a clockwise direction. If a pin 137 is disposed in one of the holes 138, however, the corresponding pattern lift lever cannot fall to its fully

depressed position and will not be raised to its fully elevated position, but it will be shifted or held in a neutral position where neither of teeth 92 or 93 engage the ratchet wheel. Under these circumstances, 70 of course, and with this dog 91 in its neutral position, the ratchet wheel 76 will not be given a step by step rotation in either direction, the shaft 76 will be held from rotation, and obviously the cam 81 will not shift the 75 needle bed at all. When the ratchet wheel 76 is given a step by step counter-clockwise rotation, the needle bed will be shifted in one direction through its range, that is according to the number of teeth with which 80 the ratchet wheel 76 is provided. If, on the contrary, the pattern lift lever is raised to its highest position, a counter-clockwise rotation will be given to the ratchet wheel 76 which will act to draw the needle bed in the 85 reverse direction. As before remarked, in the neutral position of the dog 91, no motion will be given to the needle bed whatsoever. I have illustrated a ratchet 80 which permits the needle bed to be given a step by 90 step shifting movement of four needles in either direction, but it will be understood that the cam might be made to give a shifting movement of less than four or more than four needles.

Whenever a stop pin 140 strikes the trip lever 64, it causes the arm 67 to be shifted upward, lifting the bar 68 from its engagement with the latching plate 72, whereupon the spring 70 will cause this bar to shift 100 longitudinally, rotating the member 34 and oscillating the arm 40 and releasing the clutch between the driving shaft and the driven shaft of the machine, thus immediately stopping the machine. By inserting 105 the automatic stop pin 140 in any of the holes 139, it automatically brings the machine to a stop and it is possible to insert as many of these pins as the need requires so that if necessary and desirable the machine 110 can be stopped 250 times for each revolution of one of the pattern wheels. This stoppage of the machine is for the purpose of permitting the machine to be stopped at any number of rounds or courses as required so as to 115 change yarn, deck, widen, or fashion the goods being made on the machine, which, of course, is done by hand, and furthermore these stops act as automatic counters so as to stop the machine after a certain number 120 of courses have been knitted so that garments or work may be made of uniform length.

I have heretofore referred to the cams 124 and 103 as if they are two separate cams, 125 but as a matter of convenience it is preferable to make these cams 103 and 124 in one integral piece (see Figure 21). Obviously, however, I do not wish to be limited to this. It is also preferable to dispose an anti-fric- 130

tion thrust bearing between the cone clutch 18 and the bearing for shaft 15 and I have 5 illustrated in Figure 14 for this purpose a ball carrier 146 supporting a number of balls 147, and surrounding the shaft 15 and on each side of this ball carrier are disposed the annular disks 148. By this means nearly all friction and hard running are done away with. A thrust bearing at this point makes 10 the machine easier to run and therefore cheaper in cost, saves power and does away with all troubles and friction caused by the pressure of clutch, which in other types of machines for this purpose is very great. 15 Preferably the double cam composed of the cams 103 and 124 is provided with a hub 149 and is keyed to the shaft 126 and is held in place on this shaft by means of a spring 150, as illustrated in Figure 21. While this is a 20 preferable manner of holding the cam in place, I do not wish to be limited thereto.

The operation of the machine is as follows: The handle 28 may be used for the purpose of turning the shaft 26 over by hand 25 for any number of times desired but ordinarily the machine is run by power, this power being taken from any suitable source, and as illustrated is transmitted to the pulley 21 from an electric motor. It will be 30 understood, however, that power might be transmitted directly to the gear wheel 19 if desired. In fact, I do not wish to be limited to any particular manner of transmitting power to the shaft 25, except that a clutch 35 should be used between the power transmitting wheel 19 and this shaft. Such a clutch is designated 18. Previous to the operation of the machine the pattern pins 137 are inserted into the holes 136 and 138, according 40 to the manner which will be stated a little later, and the stop pins 140 are disposed within the holes 139. The clutch is then shifted by means of the handle 41 so as to cause the operation of the machine. The 45 carriage travels back and forth in the usual manner above the needle beds and the movable needle bed 9 remains stationary, provided the pattern lift levers 105 are raised to their intermediate positions by pins in the 50 holes 138. When, however, a pin in one of the holes 136 strikes the corresponding pattern lift lever, the lever will be lifted and this will cause the ratchet 75 to be shifted one step. If there are two pins in two adjacent 55 holes 136, the ratchet wheel 76 will be shifted two steps. If there are three pins, three steps, and four pins, four steps. Thus during one, two, three or four courses the movable needle bed will be racked in one 60 direction. If now the pattern lift lever 105 should drop all the way down, due to there being no pins in the holes 138, the dog 91 will operate the ratchet wheel 76 in the reverse direction for one, two, three or four 65 steps and the shiftable needle bed will be

shifted back one, two, three or four needles in the reverse direction to that in which it was first shifted. If, however, there are pins in the holes 138, the feed dog 91 will be held in a neutral position and will not affect the movable needle bed at all. Thus 70 it will be seen that by arranging the pins in the holes 136 or 138 or leaving out these pins altogether, the movable needle bed may be racked forward one, two, three or four 75 needles or racked backward in the reverse direction, or the needle bed will be held in the position to which it has been shifted during any number of courses. The stop pins 139 cause the machine to stop at any desired 80 point for changing the yarn, decking, widening or fashioning, these stop pins operating in the manner heretofore described.

The setting of the pattern and stop pins in the pattern wheel is as follows: In setting up these wheels, they are set just as though they were one wheel, each tooth on each wheel corresponding to one course or round of the machine. As an example, assume that it is desired to make a garment 90 on the machine that has 250 courses or rounds. You would in this case use wheel 115 only, as this wheel has 250 teeth on it, although each wheel may have a greater or less number of teeth if desired. For making a garment or article with 200 rounds, all of the teeth on wheel 115 would not be used. Therefore, in making a number of these garments it is obvious that you would have to build or continue on on wheel 116. You 100 would have 250 courses on wheel 115 and 250 courses on wheel 116, or 500 courses in all. You would therefore use 200 of the perforations 136 or 138 on wheel 115 and there would be 50 of these pairs of perforations, or 105 in other words 50 courses left. This 50 courses is continued on wheel 115 so that this wheel has made a complete revolution and 50 courses have been knitted on the second garment. At this point, the pin or stop 110 141 has come in contact with the pin or stop 142. This occurs just as the feed dog 126 reaches the omitted tooth 135 so that when the wheel 115 comes to a stop, the wheel 116 is started or shifted past its omitted tooth. Wheel 116 therefore then starts up. 50 courses on the second garment have been made on wheel 115 and this leaves 150 rounds or courses on wheel 116. There are 100 courses left on wheel 116 which are not used 115 at all, although wheel 116 keeps right on working until it comes to the 250th tooth or the point 135 where the tooth is omitted. This allows the wheel to come to a standstill. Thus two garments are made with this 120 setting.

To take another example, if you wish to make articles having each 205 rounds or courses, the wheel 115 is set up 205 settings, which will make a complete garment. The 130

balance or 45 courses is controlled by wheel 115 and when that is completed the wheel 116 is started for the balance or 160 courses. Then by putting in a special starting pin X in any one of the perforations 139, wheel 115 is tripped off and wheel 116 runs without any pins to the starting point, where it stops. The perforations 139 extend entirely through the wheel and this special starting pin is inserted from outside. Thus the pin X may be screwed in any one of 249 holes. The object of this arrangement is to get the required number of rounds which could not be had with a single wheel with any set number of teeth as you could not make up except by this method.

The pattern pins are set as follows: As before explained, when there are no pins disposed in the openings 137 and 138, the corresponding pattern lift lever will drop down to its full extent so that the tooth 92 will engage the ratchet wheel 76. When there is a pin disposed in any of the holes 138, this pin when it strikes pattern lift lever will lift the lever to a neutral position. When there is a pin disposed in the outer row of holes 136, then the pattern lift lever will be lifted and the feed dog will be shifted to its highest position so that the tooth 93 will engage the tooth on ratchet wheel 76. Thus by disposing the pins 137 in the holes 136 or 138 or removing the pins entirely from said holes, the ratchet wheel 76 and therefore the needle bed may be shifted in one direction or the other or not shifted at all. As an example and taking 12 holes 136 and 138, the pins might be arranged as follows:—

40 Courses	1	2	3	4	5	6	7	8	9	10	11	12
Holes 136	x	0	x	0	x	0	x	0	0	x	0	0
Holes 138	0	0	0	0	0	0	x	0	0	x	0	0

In #1 pair of holes a pin is placed in the hole 136. In the second radial row of holes no pins are placed, in the third radial row a pin is placed in opening 136, in the fourth no pins are placed, in the fifth and seventh pairs a pin is placed in the uppermost holes, in the eighth a pin is placed in opening 138, in the ninth there are no pins, in the tenth a pin is placed in opening 136, in the eleventh a pin is placed in opening 138, and in the twelfth round or course no pins are used. The action of this will be that in the first course the ratchet wheel 76 will move one step in one direction, in the second course the ratchet wheel will move one step in the opposite direction, in the third course it will reverse its movement and move one step in the first named direction, in the fourth course it will move in the opposite direction, in the fifth course in the first named direction, and so on until the seventh course is reached. At the eighth course, there being a pin in the

lower row of holes 138, the dog 91 will be shifted to neutral so that the ratchet 76 will not be moved, in the ninth course the ratchet wheel will be shifted in the reverse direction, in the tenth course it will be shifted forward again, in the eleventh course it will remain as it was shifted for the tenth, and in the twelfth course it will be shifted back again to its original position. In other words, correlating the table given above with the movements of the dog 91, in the first course the dog will be up, in the second course down, in the third course up, in the fourth down, in the fifth up, in the sixth down, in the seventh up, in the eighth course the dog will be in neutral position, in the ninth course the dog will be down, in the tenth course the dog will be up, in the eleventh course the dog will be in neutral position, and in the twelfth course the dog will again be up. It follows therefore that the needle bed will be racked each round on seven rounds and stand still on the eighth round, the ninth round it will rack again, in the tenth round it will rack, in the eleventh it will stand still, and in the twelfth round rack.

By simply changing the pins to suit the different patterns, any pattern desired which may be formed by racking may be made. By the use of these pattern wheels I have provided means whereby the machine may be set up to do any work very simply, accurately and quickly. The setting of the pattern may be accomplished in about half the time it takes to set up a chain pattern machine and after the pattern has been decided upon or made up the machine may be set up ready to run in about five to ten minutes. It is possible with this machine to make any of the following garments or articles: backs, fronts, sleeves, pockets, cut collars, borders, "zig-zag," "French rack" or any of the many "racks" which are required to be used in this class of machine. In fact, the pattern wheels will permit the machine to make anything that is possible to me made on a flat bed knitting machine and do it automatically.

It will be noted that I have eliminated springs, chains, cams and unnecessary parts. The various members of which the machine is constructed are simple, stout, and there is no part which is so delicate as to be liable to breakage or getting out of order. The pattern and stop pins are slipped into the tapped holes for them and then held in place against accidental displacement by the annular guard plate. It is obvious that the principle of my mechanism might be applied as an attachment to knitting machines already built or that they may be complete with the knitting machine. It will be seen also that I have provided means for permitting the machine to be operated by power

and provided an automatic racking mechanism, automatic counting mechanism, and automatic stopping mechanism.

While I have illustrated a mechanism which in actual service has been found thoroughly effective, it is obvious that many minor changes might be made in the details of the machine without departing from the principle thereof as stated in the accompanying claims.

I claim:—

1. A flat bed knitting machine having a bodily shiftable needle bed and means for racking the needle bed automatically including a plurality of rotatable pattern controlling members movable through a closed path, means on each pattern controlling member for stopping it when it has moved through its entire path of movement, and means on each of said pattern controlling members for causing the automatic starting of another pattern controlled member upon the completion of movement of the first named member.

2. A knitting machine having a shiftable needle bed and means for shifting the needle bed automatically including a plurality of pattern wheels, each having adjustable pattern controlling members, and means on each pattern wheel for causing the automatic starting of an adjacent pattern wheel when the first pattern wheel has made a complete revolution.

3. A knitting machine having a shiftable needle bed and means for shifting the needle bed automatically including two pattern wheels, each having adjustable pattern controlling members, means on each pattern wheel causing its stoppage when it has made a complete revolution, and means on each pattern wheel automatically causing the starting of the other pattern wheel upon the stoppage of one pattern wheel.

4. A flat bed knitting machine having a bodily shiftable needle bed and means for racking the needle bed automatically including an oscillatable member, an oscillatable ratchet wheel operatively connected thereto to oscillate it and having two series of relatively reversed teeth, a feed dog therefor having upper and lower teeth adapted to engage with the two sets of teeth of the ratchet wheel, a power actuated oscillatable member supporting said feed dog, a pattern wheel, means on said member for giving a step by step rotation to the pattern wheel, and adjustable pattern controlling members carried by the pattern wheel and adapted, according to their position, to bring either of the teeth of the feed dog in engagement with the ratchet wheel or to dispose the teeth of said feed dog in a neutral position.

5. A flat bed knitting machine having a bodily shiftable needle bed and means for

70 racking the needle bed automatically including an oscillatable ratchet wheel having two sets of reversed ratchets, a dog having two teeth, each coacting with one of said sets of ratchets, a pattern wheel having peripheral teeth, a power operated oscillatable member having a dog engaging with the teeth on the pattern wheel to thereby give the pattern wheel a step by step movement, said oscillatable member being operatively connected to the first named feed dog to reciprocate it, and adjustable means 75 on the pattern wheel for shifting the feed dog to bring either tooth into engagement with its corresponding set of ratchets or shifting the feed dog to a neutral position out of engagement with the ratchet wheel.

6. A flat bed knitting machine having a bodily shiftable needle bed and means for racking the needle bed automatically including an oscillatable ratchet wheel having two sets of reversed ratchets, a dog having two teeth, each coacting with one of said sets of ratchets, a pattern wheel having peripheral teeth, a power operated oscillatable member having a dog engaging with the teeth on the pattern wheel to thereby give the pattern wheel a step by step movement, said oscillatable member being operatively connected to the first named feed dog to reciprocate it, the pattern wheel being provided with two series of sockets, each series of sockets having a socket for each tooth of the pattern wheel, the sockets of one series being radially disposed with relation to the sockets of the other series, pins adjustable in the two series of sockets, and means engageable by said pins acting to shift the feed dog to move either one of its teeth in engagement with the appropriate series of ratchet teeth or to shift the feed dog to a neutral position entirely out of engagement with the ratchet teeth.

7. A flat bed knitting machine having a bodily shiftable needle bed and means for racking the needle bed automatically including an oscillatable ratchet wheel having two sets of reversed ratchets, a dog having two teeth, each coacting with one of said sets of ratchets, a pattern wheel having peripheral teeth, a power operated oscillatable member having a dog engaging with the teeth on the pattern wheel to thereby give the pattern wheel a step by step movement, said oscillatable member being operatively connected to the first named feed dog to reciprocate it, the pattern wheel being provided with two series of sockets, each series of sockets having a socket for each tooth of the pattern wheel, the sockets of the two series being arranged in radial alignment with each other, pins adjustable in the two series of sockets, a pattern lift lever disposed to engage the feed dog to shift it and having a portion thereof adapted to be disposed in

the path of movement of said pins whereby to shift the feed dog into engagement with either set of ratchets or into a neutral position out of engagement with either set of ratchets.

8. A flat bed knitting machine having a bodily shiftable needle bed and means for racking the needle bed automatically including an oscillatable ratchet wheel having two sets of reversed ratchets, a dog having two teeth, each coacting with one of said sets of ratchets, a pattern wheel having peripheral teeth, a power operated oscillatable member having a dog engaging with the teeth on the pattern wheel to thereby give the pattern wheel a step by step movement, said oscillatable member being operatively connected to the first named feed dog to reciprocate it, the pattern wheel being provided with two series of sockets, each series of sockets having a socket for each tooth of the pattern wheel, pins adjustable in the two series of sockets, a pattern lift lever pivotally mounted at one end and having a portion thereof disposed to be engaged by said pattern pins on the pattern wheel and shifted thereby, and a resiliently supported member carried upon the pattern lift lever and engaging with the feed dog.

9. A flat bed knitting machine having a bodily shiftable needle bed and means for automatically racking the needle bed including an oscillatable ratchet wheel, a dog coacting with said ratchet wheel to shift it, a pattern element, means for giving a step by step movement to the pattern element in one direction, means for reciprocating the dog and pivotally supporting it, a pattern lift lever having a portion thereof disposed to be engaged by the pattern controlling element and shifted thereby, and resilient supporting means carried upon the pattern lift lever and engaging with the said dog.

10. A flat bed knitting machine having a bodily shiftable needle bed and means for racking the needle bed automatically including an oscillatable ratchet wheel having two sets of reversed ratchets, a dog having two teeth, each coacting with one of said sets of ratchets, a pattern wheel having peripheral teeth, a power operated oscillatable member having a dog engaging with the teeth on the pattern wheel to thereby give the pattern wheel a step by step movement, said oscillatable member being operatively connected to the first named feed dog to reciprocate it, the pattern wheel being provided with two series of sockets, each series of sockets having a socket for each tooth of the pattern wheel, pins adjustable in the two series of sockets, a pattern lift lever pivotally mounted at one end and having a portion thereof disposed to be engaged by

said pattern pins on the pattern wheel and shifted thereby, a supporting member including a longitudinally extending bracket disposed beneath and operatively engaging the feed dog, said supporting member being pivoted to the pattern lift lever and being resiliently supported.

11. A knitting machine having a shiftable needle bed and means for shifting the needle bed automatically including a pattern member movable in a closed path, an oscillatable ratchet wheel operatively connected to the needle bed and having two sets of relatively reversed ratchet teeth, a feed dog embracing the ratchet wheel and having opposite teeth rigid with the feed dog, each engageable with one of the sets of teeth on the ratchet wheel, said feed dog being mounted for longitudinal reciprocation in the plane of the ratchet wheel and for oscillation in said plane, power operated means for simultaneously reciprocating the feed dog and giving a step by step movement to the pattern member, and adjustable means on the pattern member for bodily raising or lowering the feed dog to bring either of its teeth into engagement with the appropriate ratchet teeth on the ratchet wheel or shifting the feed dog to a neutral position with both of its teeth out of engagement with the ratchet wheel.

12. A flat bed knitting machine having a bodily shiftable needle bed and means for racking the needle bed automatically including an oscillatable ratchet wheel having two sets of ratchet teeth and operatively connected to the needle bed to shift it, a feed dog having two teeth, each coacting with one set of the ratchet teeth, said feed dog being mounted for longitudinal reciprocating movement and for oscillating movement, a pair of pattern wheels, pattern controlling members adjustable in said pattern wheels and adapted to oscillate the feed dog into engagement with either set of teeth or into a neutral position out of engagement with either set of teeth, and power operated means for reciprocating the feed dog and giving a step by step movement to the pattern wheels, and means for causing one of said pattern wheels to stop when it has completed a revolution and automatically starting the other pattern wheel and causing the last named pattern wheel to stop when it has completed a revolution and automatically causing the starting of the first pattern wheel.

13. A flat bed knitting machine having a bodily shiftable needle bed and means for racking the needle bed automatically including an oscillatable ratchet wheel having two opposed sets of ratchet teeth and operatively connected to the needle bed to shift it, a feed dog having two teeth, each coacting with one set of ratchet teeth, the feed

- dog being mounted for longitudinal reciprocating movement and for oscillating movement in the plane of the ratchet wheel, a pair of pattern controlling elements disposed adjacent to each other operating in parallel planes and moving through a closed path, adjustable pattern controlling members on said elements and adapted to oscillate the feed dog into engagement with either set of teeth or into a neutral position out of engagement with either set of teeth, power operated means for reciprocating the feed dog and giving a step by step movement to the pattern elements, means located on each element for causing each of said pattern elements to stop when it has completed a revolution and automatically starting the other pattern element and causing the last named pattern element to stop when it has completed a revolution and automatically causing the starting of the first named pattern element, said means comprising a member disposed on one pattern element and adapted to engage a like member on the other pattern element just before the first named pattern element has completed a revolution and come to a stop to thus start the second named pattern element.
14. A knitting machine having a shiftable needle bed and means for shifting the needle bed automatically including a pattern wheel having a circumferentially extending series of sockets in one side face thereof, pattern pins insertible in said sockets, and a guard detachably engaged with the pattern wheel and normally disposed over said pattern pins and preventing their release from the sockets.
15. A knitting machine having a shiftable needle bed and means for shifting the needle bed automatically including two rotatable pattern elements disposed in parallel planes and movable in a closed path, each of said pattern elements having adjustable pattern controlling members and each of said pattern elements having ratchet teeth, means common to both of said elements for giving a step by step movement to said elements and including a reciprocatable feed dog engaging the teeth and coacting with both of said elements, the ratchet teeth of each pattern element having one tooth cut out whereby said pattern element shall make a complete revolution under the action of the dog and stop, the confronting faces of the pattern elements having inwardly projecting members, each disposed in the path of movement of the other and each disposed in radial alignment with the cut out tooth of the corresponding pattern element whereby to cause the automatic starting of one pattern element upon the automatic stoppage of the other pattern element.
16. A knitting machine having a shiftable needle bed and means for shifting the needle bed automatically including two pattern wheels having adjustable pattern controlling members, each pattern wheel having ratchet teeth upon its periphery, a power operated reciprocatable feed dog engaging the teeth of both sets of pattern wheels, each pattern wheel having one tooth cut out whereby said pattern wheel shall make a complete revolution under the action of the dog and stop, the confronting faces of the pattern wheels having inwardly projecting members, each disposed in the path of movement of the other and each disposed in radial alignment with the cut-out tooth of the pattern wheel whereby to cause the automatic starting of one wheel upon the automatic stoppage of the other wheel.
17. In a knitting machine, a pattern controlling wheel having a circumferentially extending series of ratchet teeth and having two circumferentially extending series of sockets on one face of the wheel, pattern controlling pins insertible in said sockets, a third circumferentially extending series of sockets, knitting machine controlling pins operating independent mechanism from the pattern controlling pins and insertible in any one of said last named sockets, and means engaging the ratchet teeth of the pattern wheel to give the pattern wheel a step by step rotation, the sockets of all of the series being disposed in radial alignment with each other and with a corresponding ratchet tooth.
- In testimony whereof I hereunto affix my signature.
- EDWARD FRANK CUMISKEY.
